United States Patent Office

Des. 228,345

Patented Sept. 11, 1973

228,345

CONTAINER CLOSURE

Eugene Kleinman, Montvale, N.J., assignor to Kayser-Roth Corporation, New York, N.Y.

Filed July 31, 1972, Ser. No. 276,861

Term of patent 14 years

Int. Cl. D9—07

U.S. Cl. D9—264

FIG. 1

FIG. 2

FIG. 3

FIG. 4

FIG. 5

FIG. 1 is a perspective view of a container closure embodying my new design;

FIG. 2 is a top plan view thereof;

FIG. 3 is a side elevational view thereof;

FIG. 4 is an end elevational view thereof; and

FIG. 5 is a bottom plan view thereof.

I claim:

The ornamental design for a container closure, as shown.
